VEHICLE END CONSTRUCTION

William M. Sheehan, Merion, Pa., assignor to
General Steel Castings Corporation, Granite
City, Ill., a corporation of Delaware

Application October 3, 1932, Serial No. 635,904

16 Claims. (Cl. 213—9)

This invention relates to railway cars and particularly cars for mine, quarry, or similar service, and consists in improvements in the construction of the underframe end members for this type of vehicle.

In certain types of cars, such for instance as those used in mining operations, it is desirable to obtain the maximum loading capacity without increasing the external dimensions of the car, these dimensions being restricted by the height and width of the passage through which the car passes, by the length of elevator cages in which car must be moved, and by the sharpness of curves in the track where the vehicle is operated on rails. It has been suggested to increase the capacity of mine cars by lowering the floor, suitable pockets and depressions being provided for wheels and other under equipment. Mine cars at present in use frequently utilize draft and buffering devices which extend a substantial distance along the center line of the car and prevent lowering of this portion of the floor.

My copending application, Serial No. 602,925, filed April 4, 1932, illustrates a novel draft and buffering device which is located substantially outside the end wall of the car. However, such a device must be shaped and positioned in a manner to be used with cars having the present type of draft and buffering equipment.

One object of the present invention is to provide a housing suitable for mounting a draft and buffering device generally similar to that illustrated in the above-mentioned copending application.

Another object is to provide a housing that will allow the draft and buffering device to extend within the line of end lading limit of the car but at the same time permit a substantial part of the lading floor to be below the level of the device.

Another object is to provide a car underframe end sill having an intermediate hollow box-shaped part suitably reinforced for accommodating such a device.

Another object is to provide a housing for a draft and buffering device arranged to receive draft forces at points spaced substantially transversely of the structure.

Another object is to provide means for decreasing shear stress concentration upon the bolts which anchor the buffer beam to the end sill.

Still another object is to provide a car end construction in which the connecting draft link can be swung clear as the buffer faces are brought together and then moved into its proper coupling position, thus increasing the safety factor by avoiding the necessity of guiding the connecting

link into position during the coupling operation.

These objects and others are attained substantially by the structure illustrated in the accompanying drawing in which—

Figure 1 is in part a top view and in part a horizontal section on the line 1—1 of Figure 2 and illustrating the invention.

Figure 2 is in part an end elevation and in part a vertical transverse section taken on the line 2—2 of Figure 1.

Figure 3 is a vertical longitudinal section taken on the line 3—3 of Figure 1, portions of an adjoining vehicle being shown in broken lines.

Figures 4 and 5 are similar views taken on the corresponding section lines of Figure 1.

The draft and buffering device illustrated in the figures embodies many of the features of the device shown in my copending application Serial No. 602,925 and includes spaced transversely disposed draft and buffer members 1 and 2, respectively, having opposed spring seats 3 and 4. The draft member 1 is normally seated against the vertical wall 5 of the end sill 6, to be described hereafter, and has a restricted outwardly projecting bifurcated portion 7 extending within 25 buffer member 2 between the spring seats 4. The buffer member has restricted intermediate portions 8 overlying the draft member between the spring seats 3 and vertically spaced lugs 9 projecting sidewardly from the transverse extremities thereof adjacent spring seats 4. The draft and buffer members are yieldingly held apart by means of coiled springs 10 and the movement thereof longitudinally of the vehicle is limited 30 by the wall 5 and anchoring bolts or pins 11.

Projecting outwardly from the buffer member is a restricted buffer plate part 12 having a front opening 13 for receiving the draw bar 14 secured between the projecting jaws 7 of the draft member by a draw bar pin 15 extending through aligned 40 elongated openings 16 in the buffer beam and through closely fitting openings in the draft beam. Figure 3 shows adjacent vehicles each equipped with the novel draft and buffering device. However, the flanges 12a on the buffer member are 45 disposed to cooperate with other types of buffers at present in use. The sides of member 12 are open a sufficient distance rearwardly of flange 12a to permit draw bar 14 to be swung sidewardly in opening 13 to clear the buffer member on the adjacent car during coupling and following contacting of buffers to be swung into coupling position, thus avoiding the hazardous necessity of guiding the draw bar into place during the coupling operation.

The draft and buffing device is housed within a hollow box-shaped part of the end sill 6, which part includes the vertical inner wall 5 and side walls 17 merging with the inner wall 5 in substantial curves 18. Extending along the top wall 19 of the housing is an upright rib 20 for mounting the car end wall 21, the rib 20 being located outwardly of wall 5 between the same and the buffer flanges 12a. Pads or ribs 22 are provided on the inner surfaces of the top web 19 and the bottom web 23 for limiting the vertical play of the draft and buffing device within the housing. The space 32 between the edges of the spring seats 3 and 4 is preferably less than the sum of the normal distances between the individual spring coils so that the springs cannot "go solid" and this space is also less than the space 33 between the outer ends of the draft beam projections 7 and the flanges 12a so that these latter-mentioned parts will not contact when the springs are compressed.

A portion of the flooring 24 of the car adjacent the end sill inclines diagonally upward, as at 25, and merges with the top web 19 of the end sill adjacent its intersection with the vertical inner wall 5. The construction shown is particularly adapted for fixed ends and rotary dumping, but where end dumping is desired, an end door can be substituted for wall 21 and flange 20 and incline 25 would be made less abrupt in order to allow easier discharge through the end door. Diagonal portion 25 and wall 5 are braced by flanged ribs 26 in substantial alignment with spring seats 3 and 4 on the draft and buffer beams and these members cooperate to form a rigid angular reinforcement extending along the rear surface of the end sill. The outer wall 21 of the end sill has portions 28 extending diagonally outward and merging with each side wall 17. The bottom web of the sill extends downwardly at an angle adjacent portions 28 of the front wall to merge with the deepened bottom web 23 of the housing.

Extending inwardly from the side walls 17 between the lugs 9 of the buffer beam are ribs or lugs 29 which are reinforced by ribs 30 extending in alignment therewith from walls 17 to diagonal portions 28 of the end sill outer wall. Anchoring elements 11 are secured in the top and bottom walls of the housing and extend through elongated openings 31 in the lugs 9 and through the interposed lugs 29. These interposed lugs serve to decrease the shear stress concentration upon the bolts, these being subjected to quadruple shear instead of double as would be the case if the intermediate lugs were eliminated. Draft forces are distributed through the transversely spaced bolts 11 to the end sill, these forces being carried by the flanged ribs 26 and by the floor 24 of the car. Buffing forces are carried through the wall 5 and the flanged ribs 26 to the vehicle floor.

I have illustrated the invention as applied to an integral mine car underframe structure, but it will be understood that many of the features thereof may be used advantageously with a built-up underframe. The novel end sill housing may be utilized for either a draft or a buffing device, or a device for transmitting all longitudinal forces, as shown.

What is claimed is:

1. A vehicle end structure including a substantially box-like part for housing a longitudinal force transmitting device, the top, bottom and sides of said part forming end sill elements, and a superstructure end wall member extending along the top wall of the structure and located outwardly of the inner wall of said box-like part, the

portion of said top wall inwardly of said member forming a portion of the vehicle floor.

2. A dump car underframe end structure including flooring, and an end sill having a box-shaped part forming a housing for a longitudinal force transmitting device, said flooring being inclined upwardly adjacent said sill and merging with the top wall thereof and cooperating with the rear wall of said box-shaped part to form an angular reinforcement along the rear surface of said sill.

3. In combination, a vehicle underframe structure including an end sill having a box-shaped hollow part, flooring inclined upwardly adjacent said sill and merging with the top wall thereof adjacent the inner wall of said hollow part, and ribs extending between said inclined flooring and said inner wall, and a longitudinal force transmitting device in said hollow part and including spring seats in alignment with said ribs, said inclined flooring, rear wall and ribs forming a rigid reinforcement for said end sill.

4. A vehicle end sill structure including a part for receiving a draft and buffing device, vertically spaced members in said part arranged to receive an element for anchoring a draft and buffing device, and a lug projecting from a wall of said part between said members and arranged to engage said element, said lug serving to decrease shear stress concentration in said element.

5. A vehicle end sill structure including a box-shaped part for housing a draft and buffing device, transversely spaced pins extending between the top and bottom walls of said part for anchoring said device, and lugs projecting from said part between said walls and engaging said pins, said lugs serving to decrease shear stress concentration in said pins.

6. In combination, a vehicle end sill structure including a hollow part, and a longitudinal force transmitting device housed in said part and including a buffer beam having lugs projecting from the transverse extremities thereof, and pins anchored in the top and bottom walls of said part and extending through said lugs.

7. In combination, a vehicle end sill structure including a hollow part, a draft and buffing device housed in said part and including a buffer beam having vertically spaced lugs projecting from each transverse extremity thereof, a lug projecting from said part between adjacent buffer beam lugs, and anchoring pins extending through the top and bottom walls of said part and through said lugs, said lugs serving to divide shear stresses in said pins.

8. In combination, a vehicle end sill structure including a hollow box-like part and a superstructure end wall member extending above the top wall of the sill and located outwardly of and above the rear wall of said hollow part, a draft and buffing device in said part and including a transversely disposed buffer beam having a restricted buffering plate part projecting outwardly of the sill, and a drawbar pin in said projecting part.

9. A vehicle end sill structure including an outwardly projecting box-like intermediate part for housing a draft and buffing device, portions of the outer wall of said structure extending diagonally outwardly and merging with the side walls of said box-like part to form angular reinforcements for said part.

10. A vehicle end sill structure including an outwardly projecting box-like intermediate part for housing a draft and buffing device, portions of

the outer wall of said structure extending diagonally outwardly and merging with the side walls of said box-like part to form angular reinforcements for said part, transversely spaced elements in the top and bottom walls of said part near said side walls for mounting pins for anchoring said device, and lugs projecting from said side walls between said elements and arranged to engage said anchoring pins to decrease shear stress concentration therein.

11. A vehicle end sill structure including a hollow box-like intermediate part for housing a draft and buffering device, portions of the outer wall of said structure extending diagonally outwardly and merging with the side walls of said box-like part, elements in the top and bottom walls of said part near said side walls for mounting pins for anchoring said device, and a rib extending from each of said diagonal portions through the adjacent side wall of said part and having a portion located between said elements for engaging said anchoring pins to decrease shear stress concentration therein.

12. As a new article of manufacture, an integral cast metal structure comprising a vehicle underframe end sill member including a hollow box-like part forming a housing for a draft and buffering device, and a floor member sloping diagonally upwardly and merging with the upper surface of said sill and the rear wall of said box-like part, said flooring member and rear wall constituting a rigid reinforcement for said sill.

13. In a combined draft and buffering gear for a car, the combination with a housing open at its forward end; of a buffering head telescoped within the housing, said head being longitudinally slotted to accommodate a coupling pin; stop means for limiting outward movement of the buffering head with respect to said housing; a yoke within the housing; means within the yoke yieldingly opposing relative movement of the yoke and buffering head; and a coupling pin extending through

the yoke and held against longitudinal movement with respect to the yoke, said pin extending also through the slots of said buffering head and being movable in said slots in a direction lengthwise of the car.

5

14. In a combined draft and buffering gear for a car, the combination with a supporting casing on the car; of a yoke extending into said casing, said yoke having top and bottom arms; a hollow buffering head telescoped within the casing and enclosing said arms, said head having means thereon for guiding the yoke arms for sliding movement; cushioning means yieldingly opposing relative movement of said buffering head and yoke; and means connected to the yoke arms for coupling the car to another car.

10

15. In a combined draft and buffering gear for a car, the combination with a supporting member; of a movable buffering head slidable with respect to said supporting member; means for limiting outward movement of said buffering head and holding the same assembled with the supporting member; a yoke slidable with respect to the supporting member, said yoke having top and bottom arms guided within said buffering head; a coupling pin extending through the buffering head and arms of the yoke for limiting outward movement of the yoke with respect to the buffering head; and means within the yoke yieldingly opposing relative movement of the yoke and buffering head.

15

16. A vehicle underframe structure including an end sill with its members constructed and arranged to form a pocket for housing a draft and buffering device, a lading carrying floor member inclined upwardly from a point at the level of the bottom of said pocket and at the rear thereof to a point at the level of the top of said pocket and extending over the same, and an element of said member for mounting a superstructure end wall above said pocket, said element being located outwardly of the inner end of said pocket.
